US00D778972S

(12) **United States Design Patent** (10) **Patent No.:** **US D778,972 S**
Lowder (45) **Date of Patent:** **** Feb. 14, 2017**

(54) **GRIPPER FOR AUTOMATED RUCKERS, RERUCKERS, DERUCKERS AND/OR SKIN BRAKES** 2,622,778 A 12/1952 Poland
2,712,824 A 7/1955 Steiner
2,713,449 A 7/1955 Carmichael
2,720,055 A 10/1955 Morris

(71) Applicant: **Tipper Tie, Inc.**, Apex, NC (US)

(Continued)

(72) Inventor: **Matthew D. Lowder**, Durham, NC (US)

FOREIGN PATENT DOCUMENTS

DE 2452760 5/1976
DE 4020391 1/1992

(Continued)

(73) Assignee: **Tipper Tie, Inc.**, Apex, NC (US)

(**) Term: **14 Years**

(21) Appl. No.: **29/522,521**

(22) Filed: **Mar. 31, 2015**

OTHER PUBLICATIONS

U.S. Appl. No. 11/262,600, filed Oct. 31, 2005, Wince.

(Continued)

Related U.S. Application Data

(62) Division of application No. 29/465,191, filed on Aug. 26, 2013, now Pat. No. Des. 729,294.

Primary Examiner — Terry Wallace

(74) *Attorney, Agent, or Firm* — Christensen O'Connor Johnson Kindness PLLC

(51) **LOC (10) Cl. 15-99**

CLAIM

(52) **U.S. Cl.**

The ornamental design for a gripper for automated ruckers, reruckers, deruckers and/or skin brakes, as shown and described.

USPC **D15/199**

(58) **Field of Classification Search**

USPC ... D7/368; D15/122, 127, 199, 139; 452/29, 452/48, 30, 35, 24, 33, 37, 38; 53/389.1-389.5; D8/70, 354, 356; 30/166.3, 347, 351, 353, 30/355
CPC ... A22C 11/0254; A22C 11/005; B65B 11/045; B65B 9/20; B65B 41/04; A01F 15/0715; A01F 2015/072

FIG. 1 is a front perspective view of another embodiment of a gripper showing my design;

FIG. 2 is a side view thereof;

FIG. 3 is an opposing side view thereof;

FIG. 4 is a rear end view thereof;

FIG. 5 is a front end view thereof;

FIG. 6 is top view thereof;

FIG. 7 is a bottom view thereof; and,

FIGS. 8 and 9 are exemplary perspective environmental views illustrating the gripper in an exemplary use environment associated with a rucker.

The broken lines shown herein are for illustrative purposes only and form no part of the claimed design.

1 Claim, 7 Drawing Sheets
